DESIGN.

—o—
M. MERKLEN.
BRACKET.

No. 19,296.

Patented Sept. 3, 1889.

UNITED STATES PATENT OFFICE.

MARTIN MERKLEN, OF NEW YORK, N. Y.

DESIGN FOR A BRACKET.

SPECIFICATION forming part of Design No. 19,296, dated September 3, 1889.

Application filed August 9, 1889. Serial No. 320,284. Term of patent 7 years.

To all whom it may concern:

Be it known that I, MARTIN MERKLEN, of the city, county, and State of New York, a citizen of the United States, have invented a new and original Design for Brackets, of which the following is a specification, reference being had to the accompanying photograph, forming part thereof, in which a perspective view of my newly-designed bracket is shown.

The essential feature of my design consists of a segmental curved body, divergent volutes at the lower end of the same, a volute at the upper end, and two prongs projecting from the upper end in reverse direction of the upper volute.

A is the segmental curved body.

B are the diverging volutes at the lower end; C, the volute at the upper end.
D and E are the projections at the upper

end, extending in a reverse direction of the upper volute, one of said projections having a volute ornament F on its upper surface.

G is a Greek ovolo ornament on the sides of the bracket.

Having thus described my design, I claim as new and desire to secure by Letters Patent—

The design for a bracket herein shown and described, the same consisting of a curved body, diverging bottom volutes, a top volute, and the two projections extending in a direction the reverse of that of the upper volute, as set forth.

In testimony that I claim the foregoing as my invention I have signed my name in presence of two subscribing witnesses.

MARTIN MERKLEN.

Witnesses:

W. REIMHERR,
HENRY HUBER.
